UNITED STATES PATENT OFFICE.

FRANCIS H. BOWMAN, OF PITTSFIELD, MASSACHUSETTS, ASSIGNOR TO
STANLEY-G. I. ELECTRIC MANUFACTURING COMPANY, A CORPORA-
TION OF NEW JERSEY.

CURVE-DRAWING INSTRUMENT.

No. 841,222.

Specification of Letters Patent.

Patented Jan. 15, 1907.

Application filed December 1, 1905. Serial No. 289,839.

To all whom it may concern:

Be it known that I, FRANCIS H. BOWMAN, a citizen of the United States, residing at Pittsfield, county of Berkshire, State of Massachusetts, have invented certain new and useful Improvements in Curve-Drawing Instruments, of which the following is a specification.

This invention relates to marking devices 10 of the capillary type in which a writing fluid is continuously fed to the marking-tip, and has for its object the provision of a device of this character in which an adequate and continuous flow of fluid is positively maintained 15 without danger of blotting or flooding and in which there is a minimum amount of evaporation.

In carrying out my invention I provide as a receptacle for the writing fluid a glass tube 20 with an integral reservoir below the marking-point and having an internal capillary feed through a transparent tube. The reservoir-tube is entirely closed except for a filling-orifice, and a metallic writing-tip is sealed in 25 one end and has a transparent capillary tube extending from its inner end down into the fluid. I also provide a detachable clip provided with a trunnion whereby the pen may be mounted to move easily.

30 My invention consists, therefore, in the features of construction and in the arrangement and combination of elements hereinafter set forth, and particularly pointed out in the claims annexed to and forming a part of this specification.

35 In the drawings, Figure 1 is an elevation of a device embodying my invention. Fig. 2 is a longitudinal section thereof, and Fig. 3 is a cross-section of the same.

40 Referring to the drawings, 1 is a receptacle for the writing fluid, preferably of glass, and may be of any desired form. I prefer, however, to make it in the form of a tube closed at the ends and bent at an angle so as to be

45 substantially L-shaped. By its angular shape the reservoir is below the point or marker, and the ink will not spill under jars or vibration. A filling-orifice is provided at any convenient point, as at 2. The metallic

50 tip of the pen 3 has a fine bore and is preferably of some platinum alloy, such as platinum iridium. This metal is easily and efficiently sealed into glass and is also by reason

of its hardness a desirable metal for a pen. This tip 3 is first sealed into the glass capillary 4 and then both are sealed into the combined reservoir and protecting-tube. The capillary tube 4 is bent to conform to the shape of the tube 1 and extends down into the fluid 5 and adjacent to the closed end of 60 the tube. This tube 4 is likewise of glass and is therefore transparent, thus permitting easy inspection. In starting the pen it is an advantage to be able to see the interior of the capillary tube throughout its length, as sometimes air-bubbles or sediment matter get drawn into the capillary, and I consider it of great convenience to be able to see where such are. Dislodgment thus becomes easy.

As a means for attaching the pen to the recording device on which it is to be used I provide a detachable metallic clip 6, having prongs 7 and 8 and provided with a trunnion 9, whereby the pen may be pivoted, if desired, so as to be moved away from the recording-sheet and effect a yielding marking contact with the recording-surface.

Another very important feature is that the glass capillary tube is protected by the surrounding heavy glass reservoir throughout 8c its whole extent.

It will be seen that I have provided a very cheap and efficient marking-pen. By making the receptacle of glass it can easily be made into any desired shape and size, and it 85 will always be possible to know just how much fluid remains in the receptacle and where any foreign or dry matter has lodged. The short metallic tip affords a very durable and reliable marking-pen and can be easily 90 cleaned by a fine short wire with no bends to interfere, a point which will be easily appreciated by those who have used capillary pens, while the capillary tube extending down into the receptacle and the shape of the device as 95 a whole assure a positive feed without danger of flooding or blotting.

By making the receptacle entirely closed, except for a small filling-orifice, a minimum of evaporation is assured, while at the same 100 time it is impossible for the fluid to be spilled by jarring or other accident to the receptacle during adjustment or when in use.

What I claim as new, and desire to secure by Letters Patent of the United States, is— 105

1. A marking-pen comprising a glass re-

ceptacle closed at one end and having a metallic ink-duct sealed in the other end.

2. A marking-pen comprising a glass receptacle closed at one end, and an ink-duct provided with a metallic tip sealed in the other end.

3. A marking-pen comprising a bent glass receptacle closed at one end, and an ink-duct sealed in the other end and extending within the same and terminating adjacent the closed end.

4. A marking-pen comprising a bent-glass receptacle closed at one end, an ink-duct sealed in the other end, and means for pivotally mounting said pen.

5. A marking-pen comprising a bent glass receptacle closed at one end, an ink-duct provided with a metallic tip sealed within the same and terminating adjacent the closed end, and means intermediate the ends for pivotally mounting said pen.

6. A marking-pen comprising a bent glass tube closed at one end, a metallic capillary tip sealed in the other end, and a larger tube

secured to the inner end of said tip and terminating adjacent the closed end.

7. A marking-pen comprising a bent glass tube closed at one end, a metallic capillary tip sealed in the other end, a glass capillary tube secured to the inner end of said tip and terminating adjacent the closed end, and means intermediate the ends of said glass tube for pivotally mounting the same.

8. A marking-pen comprising a bent glass tube closed at one end, a metallic capillary tip sealed in the other end, a capillary tube secured to the inner end of said tip and terminating adjacent the closed end, and a detachable clip intermediate the ends of said glass tube provided with means for pivotally mounting the same.

In witness whereof I have hereunto set my hand this 28th day of November, 1905.

FRANCIS H. BOWMAN.
